UNITED STATES PATENT OFFICE.

CHARLES M. HIGGINS, OF NEW YORK, N. Y.

BOTTLE CAP AND STOPPER.

SPECIFICATION forming part of Letters Patent No. 651,460, dated June 12, 1900.

Application filed August 27, 1895. Serial No. 560,672. (No model.)

To all whom it may concern:

Be it known that I, CHARLES M. HIGGINS, a citizen of the United States, residing at New York, (Brooklyn,) in the county of Kings and State of New York, have invented certain new and useful Improvements in Bottle Caps and Stoppers, of which the following is a specification.

My invention is more especially adapted for 10 bottles of syrupy liquids—such as mucilage, maple syrup, varnishes, &c.—from which portions are used from time to time, and one form of my invention is specially adapted for bottles of beer or other effervescent liquors and 15 produces an improved method of opening the same without gushing.

The main object of my invention is to form a secure, handsome, convenient, and inexpensive seal or closure for the bottle-neck 20 which will entirely dispense with ordinary corkage and close the mouth of the bottle perfectly water-tight for any length of time while in stock or during transportation and which can be easily opened or unsealed by the consumer and the liquid poured out in small 25 portions, as required from time to time, and the pouring-opening afterward securely covered until the next supply is needed. For this purpose I provide the mouth of the bottle with a covering-cap having a narrow diametrical slot therein, and I interpose between 30 said slotted cap and the mouth of the bottle an incisile sealing-disk forming a seal between the two, which can be readily cut out by the insertion of a knife-blade, coincident 35 with the slot in the cap, thereby forming a free pour-out opening, which when the bottle is so held that the slot is vertical permits the free outflow of a steady stream of the liquid 40 contents from the lower part of the slot, while a vent of air freely enters at the top of the slot. I pivot upon the said slotted cap a swinging valve or cover to command said slot, so that it can be swung off the slot to permit 45 the cutting of the sealing-disk and the out-pour of its contents and can be again swung over the slot to close the same and form a temporary seal until the pour-out of another portion is desired. I strike up a tubular rivet 50 out of the cap and integral therewith, on which said swinging valve is pivoted and by which it is secured movably on the cap. I also pro-

vide the swinging valve with a manipulating tip and stop to limit its closing motion.

My invention therefore consists, mainly, 55 in the features above outlined and also partly in the special construction of the sealing-disk adapted to bottles of beer, &c., as hereinafter fully set forth and claimed.

In the drawings, Figure 1 presents a plan 60 view of my improved stopper applied to a bottle and shown with the valve closed. Fig. 2 is a similar view with the valve swung off to expose the slit and the incisile sealing-disk below. Fig. 3 is a cross-section on *xx* looking in the direction of the arrow. Fig. 4 is a cross-section on *oo* viewed in the opposite direction, indicated by the arrow. Fig. 5 is a cross-section lengthwise of the pour-out slot or on *yy* in Fig. 1; Fig. 5^a, plan views 70 of the disks used in the construction shown in Fig. 5. Fig. 6 is a side elevation of a bottle provided with my improved cap and shown in the position in which the contents are being poured out through the pour-out slot in 75 cap and disk. Fig. 7 is a plan view of a modification in which the cap is provided with a large circular opening. Fig. 8 is a plan view of one form of my stopper specially adapted for beer or other drinkable liquid under pressure, and Fig. 9 is a cross-section thereof.

In the drawings, *A* indicates the bottle or other receptacle, and *a* the neck thereof, and *B* indicates a cap or cover, preferably a screw-cap, suitably fixed or secured on the neck, 85 preferably by means of an ordinary screw-thread, as indicated. This cap is perforated with a narrow slot *c*, which preferably extends across and through the center of the cap or diametrical thereof, or substantially 90 so, as shown in full lines in Fig. 1 and in section in Figs. 3, 4, and 5. This slot is preferably made as long as admissible by the diameter of the cap and the bore of the bottle-neck, preferably about the same length, or a 95 little less than the internal diameter of the bottle-neck, as seen in Fig. 5. This slot is preferably straight on the sides and angular or V-shaped on the ends for a reason which will be hereinafter apparent. On the top of the cap is pivoted a swinging valve or closer *C*, which has preferably the form of an elbow-lever or approximately of *L* shape, as shown well in Figs. 1 and 2, pivoted at the end of

the short arm at one side of the slot and near one end thereof on a vertical axis near the rim of the cap, so that it can be swung to one side in a plane parallel with the top of the 5 cap and across the slot into a position at or about right angles to the slot, and thus completely uncover the same, as shown in Fig. 2, and can be again swung back in line with the slot, so as to fully cover and conceal the same, 10 as shown in Figs. 1 and 3. This valve C is pivoted on a tubular rivet g, struck up out of the top of the cap B and integral therewith, as shown best in Fig. 3, said rivet passing through a pivotal hole in the short arm of the 15 valve-lever C, as seen in Fig. 3, and it is then swaged or flared down about said pivot-hole, as seen in Fig. 4, thus holding the valve in a most simple and secure manner to the cap and permitting its free pivotal movements 20 thereon and without the use of any pivot-pin or part separate from cap and lever, thus contributing materially to cheapness and simplicity of construction. It will be noted that another great advantage of this construction 25 of the pivotal part of the cap is that not only does it dispense with separate pivots and reduce cost, but it leaves the under surface of the cap perfectly smooth and flush without any protuberances. This is very important 30 where a packing disk or layer is interposed between the cap and the bottle-neck, as the pivot-point usually comes over the edge of the bottle-mouth or near the same, (see Figs. 4, 7, 8, and 9,) and where a protuberant solid 35 rivet is used it is likely to tear or puncture the sealing or packing layer when the cap is screwed on, and as it forms a protuberant bearing at one point over the edge of the bottle it prevents the cap being screwed down 40 even and level, and thus prevents a good tight joint being secured. On the contrary, on reference to Figs. 3 and 4 of the drawings it will be noted that in my construction the under side of the cap against the packing or 45 sealing layer is perfectly smooth or flush, no inner protuberance existing at the eyelet-pivot g, all the protuberance being directed outward, and hence insuring a perfectly-even bearing of the cap on the bottle, a tight joint 50 between the two, and no injury to the packing. The extremity of the valve-lever C is bent downwardly, as shown best at k in Figs. 4, 5, and 6, forming a manipulating tip or handle which overhangs the edge of the cap B and 55 enables the lever to be easily taken hold of by the fingers and swung open or closed. It will be seen that owing to the eccentric position in which the valve-lever is pivoted on the cap relatively to the slot c, as seen in Figs. 1 and 2, 60 when the valve is swung into the closed position the tip k strikes the rim of the cap and then acts as a simple and efficient stop to hold the valve in said closed position. It will be also noted that by the pivotal arrangement of 65 the valve relatively to the slot shown in Figs. 1 and 2 it is only necessary to move the valve through one quarter-revolution to fully un-

cover the slot, as seen in Fig. 2, which is a decided advantage for quick action. Now between the slotted cap and the neck or mouth 70 of the bottle I interpose a thin incisible sealing-disk f, which also serves as a packing between the two, as shown well in Figs. 4 and 5, thus forming a water-tight seal when the cap is screwed down tightly or otherwise fixed 75 over or upon the neck of the bottle, as shown clearly in Figs. 4 and 5. This disk f may be formed of waxed paper, rubber, cork, or other material and in one sheet or layer, as shown in Fig. 4; but it may also be formed in two 80 layers, as seen in Figs. 5 and 9, the upper layer f being strictly the incisible layer and being formed of some thin water-tight tenacious but easily cut, yet strong, material—such as a thin sheet of soft metal, rubber, or 85 parchment—while the lower layer f' forms the packing-layer, made of some soft elastic material like paper, felt, cork, &c., and this layer f' may be made in the form of a continuous disk, as in Fig. 9, or in an annular 90 washer, as shown in Fig. 5, serving in the latter case as a packing merely, while the thin overlying disk f forms a water-tight seal easily incisible. It will now be seen that when the slotted cap is secured upon the bottle-neck 95 with the incisible sealing-disk f or f' intact between the two, as shown in Figs. 5 and 9 and also in Figs. 3 and 4, both the pour-out slot c and the pivotal eyelet g will be covered and closed by said disk and a tight joint thus 100 made between cap and bottle, which will secure the contents of the bottle water-tight for any desired length of time and without any corkage or other sealing. When, however, it is desired to pour out any of the contents, it 105 will be only necessary to puncture and cut out the incisible sealing-disk with the point of a fine pocket-knife blade, as indicated in dotted lines in Fig. 5, following the contour of the slit in the cap, as seen in Figs. 2 and 110 5, and then cutting a narrow piece out of the disk, as shown at t in Fig. 4, coincident with said slot, thereby forming a free pour-out opening through which the liquid can be freely poured, as shown in Fig. 6, when the 115 bottle is inclined or tilted and so held that the slot is vertical. (See Figs. 2 and 6.) It will now be seen that by having the pour-out opening in the form of a narrow slot not only is less of the thin incisible disk exposed to injury, and hence the construction 120 is much stronger and more secure, but at the same time a very free exit is obtained for the liquid, which in this case is forced to assume a flat vertical stream, which gushes out 125 through about two-thirds or three-quarters of the length of the slot, while only the mere upper extremity forms the air-vent through which the air will enter very freely, as indicated in Fig. 6, insuring steadiness in the 130 liquid stream. The issuing stream being thus compelled by the narrow slot to flow out in a broad thin flat stream, yet with considerable volume and force, issues with great steadiness

and a decided trajectory, and hence flows cleanly and evenly off the edge of the cap without requiring any lip or other device to guide it, and thus falls surely into the vessel placed below to receive it, the flat stream changing to a firm round pellucid stream as it runs off the edge of the cap, as illustrated in Fig. 6. By this means the stream has no tendency to waver from side to side or run lazily down the sides of the cap and bottle, as would be the case if the pour-out opening were large and round like the usual pour-out opening of bottles, in which case the stream being wide and shallow and the opening wide or large it would have no decided trajectory, but would issue in a large sluggish or lazy stream, likely to run down the sides of the bottle and not easy to direct or maintain in any desired direction. Furthermore, the volume of the stream would be greatly influenced by slight variations in the tilt of the bottle, and thus be difficult to control, whereas with the vertical slot as described the volume of the stream is very little affected by variations in the tip or tilt of the bottle, and hence the direction and control of the stream when pouring out is made a very simple and easy operation and is one of the important advantages of this construction.

It will be noted that by having the pour-out slot arranged diametrically of the cap or nearly so the greatest possible length and capacity is thus obtained, it being desirable to have the slot as long as possible, but not wide, as will be understood. It will also be seen that by having the slot straight with angular or V ends, as shown best in Figs. 1 and 2, it becomes very easy to make a quick, clean, and easy cut in the sealing-disk with the point of a pocket-knife, as shown in Fig. 5, and thus remove a strip *t* therefrom, as shown in Fig. 4, coincident with said slot to permit the pour-out as described.

In some cases the pour-out opening in the cap may be oval, as shown in Fig. 8, but for most purposes this is not as good as the straight slot. For pasty or thick liquids the opening may be large and circular, and the swinging valve or cover may be circular, of nearly the same form and size as the top of the cap, as shown both in Figs. 7 and 8. In Fig. 7 notches *n n'* are shown in the coinciding edges of the cap and valve to permit the projection of the handle of a brush or other tool when used on pots of varnish, paste, or other materials, and yet permit the cover to be swung fully closed, as will be understood.

Figs. 8 and 9 represent the form of my stopper which is especially adapted for stoppering bottles of beer or other drinks or liquids under pressure. In this case (see Fig. 9) I form the incisive disk *f* of a thin sheet of celluloid and the packing-disk *f'* of cork. The celluloid disk is very strong and gas-proof, as well as waterproof, and when the

pour-out opening in the cap is made small or contracted, as in Fig. 8, it will be able to stand a good pressure without yielding or bursting and at the same time is comparatively soft to 70 a knife-blade and easily cut thereby. Both the celluloid and cork disks are also entirely innocuous and impart no taint or objectionable flavor to beer or other drinks. It will be seen upon reference to Fig. 9 that the cork 75 and glass only come in contact with the beer, and this cork being in a thin disk only will be inexpensive and the whole stopper far cheaper and more convenient than the usual corks and also much more easily opened than a 80 corked bottle, and yet will possess the great advantage of ordinary corkage so much desired by particular bottlers of choice beer or wines in having cork and glass only in contact therewith, as it is well known that cork 85 imparts no objectionable taint or flavor to beer or wine, while rubber or other materials do. To open the bottle of beer stoppered as shown in Fig. 9, it is only necessary to first puncture the celluloid and cork disks with 90 the point of a fine knife-blade, as shown by dotted lines, thus forming a preliminary gas-leak, through which the gas will slowly exude, and thereby relieving the pressure gradually before the liquid is poured out, and thus 95 preventing a sudden or foaming gush, which is always liable to happen in removing the ordinary cork or other stopper. When the gas-pressure is thus relieved, a simple continued movement of the knife-blade will cut 100 out a section of the celluloid and cork disks coincident with the pouring-opening of the cap, as before described, permitting the free outpour of the contents. It will be seen that this system forms, in fact, an improved method 105 of stoppering and unstoppering beer, &c., which has many advantages over the usual corkage in permitting such quick and easy opening of the bottle, and yet a gradual relief of the gas-pressure to prevent sudden or 110 foaming gush in the outpour and at the same time having the main advantage heretofore pertaining to ordinary corkage and so much desired by bottlers.

Referring to the drawings, it will be seen 115 that it is not essential to my invention that the swinging valve be used in all cases; but for most purposes it or some other form of valve or closer is desirable in connection with the pour-out slot, and of course, if desired, a 120 separate rivet may be used for pivoting the valve in lieu of the improved means shown. The cap may of course be secured on the bottle-neck by any other suitable means besides that of an ordinary screw-thread, which is 125 considered preferable.

In some cases, if preferred, the bottle may be opened without cutting the disk *f* by simply unscrewing the slotted cap and entirely removing said disk and again screwing on 130 the slotted cap and pouring out through the same, this method being particularly admissi-

ble with the construction shown in Fig. 5. When it is desired to hermetically seal the bottle again, the disk *f* and cap can be replaced as at first. In most cases, however, 5 the screw-caps will stick, particularly where adhesive liquids are inclosed, and can only be unscrewed with considerable effort, and hence the cutting out of the incisive disk will be the most simple and convenient method 10 of opening.

It will of course be understood that my improved cap or stopper is not confined to glass or other bottles, but is equally applicable to cans or packages of sheet metal or other material.

Having thus described my invention, what I claim is—

1. In a bottle-stopper, the covering-cap *B* formed with an elongated pour-out slot *c* extending diametrically thereof, the sides of said slot being parallel, and an external valve mounted on said cap for closing and opening the slot, substantially as and for the purpose set forth.

2. The combination with the covering-cap *B* adapted to cover the neck of the bottle and having the elongated parallel-sided pour-out slot *c* therein with an incisive sealing-disk interposed between said slotted cap and the 30 neck of the bottle substantially as shown and described.

3. The combination with the covering-cap *B* having elongated parallel-sided pour-out slot *c* with swinging valve *C* pivoted on the 35 cap adjacent to said slot substantially as shown and described.

4. The combination with the covering-cap *B* having elongated pour-out slot *c* having parallel sides and incisive sealing-disk *f* below 40 the cap with swinging valve above the cap

arranged and operating substantially as shown and described.

5. The combination with covering-cap *B* formed with elongated pour-out slot *c*, of the valve-lever pivoted on the cap at one side of 45 or eccentric to the median line of said slot, substantially as herein set forth.

6. The combination with the covering-cap *B* formed with the elongated pour-out slot *c* and tubular integral pivot or eyelet *g*, of a 50 swinging valve pivoted on said tubular pivot *g*, and a packing or sealing layer underlying the cap and closing the slot and eyelet *c*, *g*, substantially as shown and described.

7. The combination with the covering-cap *B* formed with an elongated pour-out opening 55 extending diametrically thereof, of a swinging valve pivoted on a vertical axis on said cap near the circumference and near one end and at one side of the pour-out opening swinging in a plane parallel with the top of the cap and having its tip *k* bent to overhang the rim of the cap, and thereby forming a stop to limit the closing position of the valve over the pour-out opening, substantially as shown and described.

8. The combination with the covering-cap *B* formed with the elongated pour-out slot *c* and eyelet *g*, of a swinging valve pivoted on 60 said eyelet, and a packing or sealing layer 70 underlying the cap and closing the slot and eyelet *c*, *g*, substantially as shown and described.

In witness whereof I hereunto set my hand in the presence of two witnesses.

CHARLES M. HIGGINS.
